PIVOTED CLOSURE LATCH

Montie A. Wallace, Fort Stockton, Tex.

Application August 30, 1956, Serial No. 607,053

3 Claims. (Cl. 292—67)

This invention relates to latch construction designed primarily for securing a closure in a closed position, the primary object of the invention being to provide a latch which will prevent accidental opening of the closure due to vibrations.

An important object of the invention is to provide a pivoted latch which is so constructed and arranged that it will be held in its active latching position by gravity, eliminating the use of springs or similar mechanism.

Another object of the invention is to provide a latch which may be readily moved to an unlatched position, should it be desired to open the closure to which the latch is attached, the latch being provided with means for holding the pivoted latch member in either its latched or unlatched position.

A further object of the invention is to provide a pivoted latch which may be swung to an inactive or unlatched position and held in such position to permit the closure to be readily swung to an open or closed position.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing

Figure 1 is an elevational view illustrating a latch constructed in accordance with the invention, as moved to its latching position.

Fig. 2 is a similar elevational view illustrating the slots of the latch with respect to the latch plate.

Fig. 3 is an elevational view illustrating the pivoted latch as moved to its unlatched position.

Fig. 4 is an edge elevational view of the latch.

Fig. 5 is a perspective view of the pivoted latch independent of the latch plate.

Referring to the drawing in detail, the latch member is indicated generally by the reference character 5 and embodies a substantially L-shaped body including the main section 6 and a laterally extended latch section 7.

The main section 6 is provided with a slot 8 disposed along the axis of the main section, the lower end of the slot 8 terminating in spaced relation with the end 9 of the slot 10 which extends throughout substantially the entire length of the latch section 7. One edge of the slot 10 is provided with an offset 11 for purposes to be hereinafter more fully described.

The latch member also includes a latch plate 12 which is elongated and is of a length to extend substantially the entire length of the main section 6, as better shown by Fig. 1 of the drawing.

This latch plate 12 is provided with openings adjacent to the ends thereof through which the securing screws 13 extend, one of the securing screws 13 passing through the slot 10, while the other screw 13 passes through the plate 12 and through the slot 8 of the main section.

2

A securing screw 13 at the upper end of the plate 12 provides a pivot pin for the latch member so that when the latch member is moved to a position as shown by Fig. 1 of the drawing, the latch section 7 will extend laterally and pass under the keeper plate 14 which is secured to the closure with which the latch is used, by means of the screws 15, which screws pass through the keeper plate 14 and are embedded in the closure frame, which in the present showing is indicated by the reference character 16.

10 The keeper plate 14 is provided with an offset portion 17 under which the latch section 7 moves.

The offset portion 11 provides the locking feature for the latch member when the latch member is held in its inactive or unlatched position, so that the latch member will be held disengaged from the keeper when it is desired to maintain the closure unlatched with the closure in its open position.

With the latch member in this position, the screw 13 at the lower end of the latch plate 12, moves into the offset portion 11, so that in order to move the latch member to its latching position, it is necessary to lift the latch member to disengage the screw 13 from the offset portion of the latch section 7, whereupon the latch may be twisted or turned in the arc of a circle, moving the laterally extended latch section 7 under the keeper, the screw 13 at the upper end of the latch plate 12 assuming a position at the upper end of the slot 8, holding the latch in its latching position against accidental displacement due to vibrations.

30 Extending from the latch plate is the pin 18 which is gripped by the operator in moving the latch member in either its latched or unlatched position.

From the foregoing it is believed that the operation of construction of the latch member will be obvious, and that further detailed disclosure of the invention is unnecessary.

What is claimed is:

40 1. A closure latch adapted to engage a keeper, said latch comprising an L-shaped latch member adapted to be secured to a closure, said latch member including a main section and a laterally extended latch section for engagement under said keeper, said sections having slots extending longitudinally thereof, the slot of said latch section having an offset portion adjacent to the end thereof, a latch plate fitted over said main section, a pair of headed securing members extending through said latch plate and slots, one of said headed securing members providing a pivot for the latch, the other headed securing member adapted to extend into said offset portion of said latch section, normally holding said latch section in an unlatched position and an operating pin extending laterally from said latch member for effecting operation of said latch member to its latched or unlatched position.

50 2. A closure latch adapted to engage a keeper, said latch comprising an L-shaped member embodying a body portion and a laterally extended latch section for engagement under said keeper, each of said sections having a slot disposed longitudinally thereof, the upper edge of one of said slots having an offset portion adjacent the end thereof, headed securing members extending through said slots, pivotally securing said latch to a closure, one of said headed securing members adapted to move into said offset portion temporarily holding said latch member in its unlatched position, and an operating pin extending laterally from said latch member for effecting operation of said latch member.

60 3. A closure latch adapted to engage a keeper, said latch comprising an L-shaped body constructed of flat metal material including a main section and a laterally extended latch section for engagement under said keeper,

65 70

said sections having slots disposed longitudinally thereof, spaced securing screws extending through the slots of said main section and laterally extended section securing said latch to a closure, one of said screws providing a pivot for said latch, the other screw guiding said latch in its pivotal movements, one of said slots having an offset portion on its upper side adjacent the end for the reception of one of said screws, normally holding said latch in an unlatched position, and a pin extending laterally from said body for effecting the operation of said latch. 10
